UNITED STATES PATENT OFFICE.

MARY STARMER, OF NEWPORT NEWS, VIRGINIA.

SAFETY CHAIN HOLDER.

Application filed December 23, 1927. Serial No. 242,102.

My present invention relates to improvements in safety chain holders involving the use of a belt buckle of standard type as usually employed on belts for personal wear by men or women.

The device of my invention is especially designed for use in supporting a watch chain and the latter may be attached to the buckle by a spring ring of the usual make, the chain 10 may be looped for attachment to the buckle, or other means may be employed for connecting the chain to the holder of the buckle in such manner that the chain is prevented from becoming detached from the buckle.

15 By the utilization of my invention, I am enabled to manufacture a combined belt buckle and safety chain holder at comparatively slight cost and by simple operations, without changing the exterior appearance of the well 20 known types of belt buckles. The buckle may be stamped, pressed, or fashioned in other suitable manner by proper tools or machines, and the holder is preferably fashioned as an integral part of the buckle.

25 My invention consists in certain novel combinations and arrangements of parts as will hereinafter be more fully set forth and claimed.

In the accompanying drawings, I have illustrated one complete example of the physical embodiment of my invention in connection with two types of belt buckle, in which the parts are combined and arranged according to the best mode I have so far devised for 35 the practical application of the principles of my invention.

Figure 1 is a face view of the buckle end of a belt for personal wear showing the inner side of the belt and showing also the chain holder as an integral part of the buckle;

Fig. 2 is a top edge view of the parts shown in Fig. 1;

Fig. 3 is a front edge view looking at the buckle end of the belt of Fig. 1; and

45 Fig. 4 is a front view of a portion of a buckled belt in which the buckle is of a modified form but also provided with the safety chain holder.

In order that the general arrangement and 50 relation of parts may readily be understood, I have shown in Fig. 1 one end of a belt 1 which may be of leather or other suitable material and provided with the usual loop 2

which is secured to the body of the belt by snap fasteners as 3. The buckle 4 which is 55 supported from the loop 2 is provided with the usual prong or tongue 5 and at the inner side of the buckle and preferably on its lower horizontal bar I provide an integral flange 6 having a slot 7 therein. This flange and slot 60 form the safety holder for the watch chain and the latter is indicated as being supported from the slotted flange. The flange 7 may be an integral part of the buckle or it may be rigidly secured thereto in suitable manner. 65 The flange projects from the bottom bar of the buckle at its inner side but is not of sufficient width to interfere with the fastening or unfastening of the belt. The watch chain may be attached to the slotted flange by the 70 use of a spring ring or by any other suitable means and of course the watch chain dangles from the safety holder somewhat as indicated in Fig. 1.

In Fig. 4, I have shown another type of 75 buckle as 8 which is carried at the looped end 9 of the belt and the perforated end 10 of the belt is secured to the buckle by the prong or tongue 11. The slotted flange is indicated by dotted lines at 12, being on the rear side of 80 the bottom bar of the buckle. The chain may be attached to this slotted flange in manner similar to that shown in Fig. 1.

As thus constructed, the combined buckle and chain holder provide a useful device for 85 supporting the chain and the usual appearance of the buckle is maintained. As thus illustrated and described, it will be apparent that the device of my invention provides a novel and useful instrumentality for the performance of its required functions. 90

Having thus fully described my invention, what I claim as new and desire to secure by Letters Patent is—

A rectangular buckle having parallel end 95 bars, upper and lower horizontal bars, a tongue on one end of the end bars and an integral slotted flange projecting inwardly from the inner edge of the lower bar for the reception and detention of a watch chain, a belt having one of its ends looped about one 100 of the end bars and having its other end passing under the other end bar and adjustably secured to the tongue.

MARY STARMER.
